VALÈRE A. FYNNE, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION-SWITCH.

1,328,990.

Specification of Letters Patent. Patented Jan. 27, 1920.

Application filed June 26, 1918. Serial No. 241,995.

To all whom it may concern:

Be it known that I, VALÈRE A. FYNNE, a subject of the King of England, residing at the city of St. Louis, State of Missouri, United States of America, have invented a certain new and useful Ignition-Switch, of which the following is such a full, clear, and exact description as will enable any one skilled in the art to which it appertains to make and use the same, reference being had to the accompanying drawings, forming part of this specification.

My invention relates to a switch for controlling the ignition circuit of an internal combustion engine, and is more particularly adapted to be used in connection with a battery system.

The object of the invention is to cause the ignition switch to be automatically opened as soon as the engine speed has fallen below the lowest operating speed, or when the engine has come to rest with the ignition circuit closed, and thus avoid useless discharge of the battery and possible damage to the spark coil.

In carrying my invention into practice, I provide means for holding the ignition switch in its closed position and place these means under the control of a device which responds to a constant unidirectional current or to a current which is infrequently interrupted or reversed, but does not respond to a current which goes through many cycles per second. In the preferred form of my invention, I make use of an electromagnet located in coöperative relation to the means which hold the ignition switch in its closed position, energize said magnet by means of the ignition current itself and locate a shortcircuited winding in inductive relation to the energizing winding of said magnet for the purpose of rendering the latter inoperative at all but very low ignition current periodicities.

In the accompanying drawings, Figure 1 diagrammatically illustrates one embodiment of my invention and Fig. 2 illustrates a modification.

Referring to Fig. 1, which shows a battery

ignition system, the primary ignition circuit comprises the storage battery 3, the low tension winding of the ignition coil 2, the timer or circuit breaker 4, the spring controlled ignition switch 5, and the energizing coil 11 of the electromagnet 9. This electromagnet is also provided with a shortcircuited winding 10 located in inductive relation to the energizing coil 11 and placed in coöperative relation to the spring 7 held in the clamp 8, provided with an armature 6 coöperating with the electromagnet 9 and adapted to hold the switch 5 in its closed position by engaging the nose 6 thereof. This switch is provided with a handle, is pivoted at 12, and when closed as shown in the figure it completes the low tension ignition circuit at the point 13. The ignition switch can be opened by hand by pushing the catch integral with the spring 7 out of engagement with the nose 6 of the switch, in which case, the spring controlling said switch will take control and bring 5 against the stop 19. The high tension side of the ignition coil is grounded at one end and connected to a distributor at the other.

The arrangement shown in Fig. 2 differs from the foregoing, in that the spring controlled ignition switch 5 is held in its closed position by the electromagnet 15. The energizing coil 16 of this magnet is connected to one pole of the battery 3, through the normally closed automatic switch 17 and the normally closed hand operated switch 20. The other end of the coil 16 can be connected to the other pole of the battery by means of the contact 14 and the ignition switch 5, connection being made only when the ignition switch is closed. The switch 17 is held closed by means of a spring clamped at 18, which spring carries an armature adapted to cooperate with the electromagnet 9 energized by the coil 11, included in the low tension side of the ignition circuit, and carrying the shortcircuited winding 10 placed in inductive relation to the coil 11.

Referring to the operation of the arrangement shown in Fig. 1, when it is desired to

start the internal combustion engine, the ignition switch 5 is closed by hand. If the primary ignition circuit happens to be open, at the timer 4 for instance, then the spring 7 will hold the switch 5 in its closed position, but if the ignition circuit is closed, then the electromagnet 9 will attract the spring 7 and release the switch 5, and it will therefore be necessary for the operator 10 to hold the ignition switch in its closed position until the engine has started. Even when the engine revolves at the lowest speed at which it will operate, the current interruptions in the primary ignition circuit 15 are so frequent that the shortcircuited coil or winding 10, in inductive relation with 11, is sufficiently effective to reduce the magnetization produced by the energizing coil 11 to such an extent as to make it impossible 20 for the electromagnet 9 to overcome the spring 7 and release the switch 5. The fact that the magnitude of the primary ignition current is very rapidly reduced as the speed of the engine increases further decreases the 25 magnetization which it is possible for the coil 11 to produce and thus make it doubly certain that the switch 5 will not be opened at any working speed of the engine. Should the engine speed now fall below its lowest 30 operating speed, then the engine will come to rest more or less rapidly, and as it does so, it will reduce the frequency of the current interruptions in the primary ignition circuit, with the result that the impedance 35 of said circuit will rapidly diminish, causing the ignition current to rise very quickly. The diminished frequency of the interruptions will reduce the damping efficiency of the shortcircuited winding 10, and this together with the increased ignition current 40 will enable the electromagnet 9 to overpower the spring 7 and open switch 5 even before the engine comes to rest. Should it, however, fail to do so, then the spring 7 45 will undoubtedly be overpowered by the electromagnet 9 when the engine does come to rest with the timer closed.

The operation of Fig. 2 only differs from that of Fig. 1 in that the electromagnet 9 50 operates to deenergize the electromagnet 15 which holds the ignition switch 5 closed instead of overpowering the spring 7 which holds said switch in its closed position. The electromagnet 15 is deenergized in Fig. 2 55 when the electromagnet 9 opens the normally closed spring controlled switch 17. Should it at any time be desired to stop the internal combustion engine provided with the ignition system shown in Fig. 2, then it 60 is only necessary to temporarily open the switch 20, thus deenergizing the electromagnet 15 and releasing the ignition switch 5. As soon as switch 20 is released, its spring will carry it back into closed position. 65 It is seen that the device which controls

the ignition switch, releasing same when the current in the ignition circuit ceases to be interrupted, is so constituted that although in circuit with the low tension side of the spark coil, yet it does not adversely affect 70 the operation of same. This result is secured by the short circuited winding 10 in inductive relation with the energizing winding 11 of the electromagnet 9 in control of the opening of the automatic ignition switch. 75 Any material inductance in circuit with the primary of the spark coil would slow down the rise of current in said coil and thus reduce the efficiency of the latter. As long as the current in the primary coil is 80 pulsating, the reactance of the electromagnet 9 is made very small indeed by the presence of the short circuited winding 10 and in this way the operation of the coil is not adversely affected. The same short circuited 85 winding prevents the automatic ignition switch from being affected to open the ignition circuit as long as the ignition current is pulsating.

Having fully described my invention, 90 what I claim as new and desire to secure by Letters Patent of the United States is:

1. In apparatus of the class described, the combination with a primary ignition circuit comprising a source of direct current E. M. 95 F., a timer and an ignition switch, of means for causing said switch to open, and means responsive to pulsating current in the ignition circuit for rendering the said first named means inoperative. 100

2. In apparatus of the class described, the combination with a primary ignition circuit comprising a source of direct current E. M. F., a timer and an ignition switch, of means responsive to continuous current for causing 105 said switch to open, and means responsive to pulsating current in the ignition circuit for rendering the said first named means inoperative.

3. In apparatus of the class described, the combination with a primary ignition circuit comprising a source of direct current E. M. F., a timer and an ignition switch, of means for holding said switch in closed position, and an electromagnet for releasing the holding means, said magnet comprising a coil in 110 the ignition circuit and a second coil in inductive relation to the first named coil. 115

4. In apparatus of the class described, the combination with a primary ignition circuit comprising a source of direct current E. M. F., a timer and an ignition switch, of means for holding said switch in closed position and an electromagnet for releasing the holding means, said magnet comprising a coil in 120 the ignition circuit and a short circuited coil in inductive relation to the first named coil. 125

5. In apparatus of the class described, the combination with a primary ignition circuit comprising a source of direct current E. M. 130

F., a timer and an ignition switch, of mechanical means tending to open said switch, a latch for holding the switch in closed position, and an electromagnet for releasing the latch, said magnet comprising a coil in the ignition circuit and a second coil in inductive relation to the first named coil.

6. In apparatus of the class described, the

combination with an ignition switch of electromagnetic means for controlling said switch, said means comprising a coil in the ignition circuit and a short circuited coil in inductive relation to the first named coil.

In testimony whereof I have hereunto set my hand and affixed my seal.

VALERE A. FYNN. [L. s.]
